UNITED STATES PATENT OFFICE.

IVAN D. THORNBURGH, OF BERKELEY, CALIFORNIA, ASSIGNOR TO AMERICAN CAN COMPANY, OF SAN FRANCISCO, CALIFORNIA, A CORPORATION OF NEW JERSEY.

ORGANIZED APPARATUS FOR GROOVING CAN ENDS AND APPLYING RING-LINERS THERETO.

1,400,580.

Specification of Letters Patent. Patented Dec. 20, 1921.

Application filed October 10, 1918. Serial No. 257,636.

To all whom it may concern:

Be it known that I, IVAN D. THORNBURGH, a citizen of the United States, residing at Berkeley, in the county of Alameda and State of California, have invented certain new and useful Improvements in Organized Apparatus for Grooving Can Ends and Applying Ring-Liners Thereto, of which the following is a specification.

The hereinafter described invention consists of an apparatus for forming a circumferential groove within the outer peripheral surface of the vertically drawn interior wall or shoulder of a can end, and positioning a cut gasket liner ring in order that the inner circumferential edge of the said liner ring will lie within the circumferential groove formed in the can end in order to be held therein by the overhang of the peripheral wall; and the apparatus comprising coacting instrumentalities for feeding or delivering an unfinished can end from a stack of ungrooved ends, forming a circumferential groove or seat in the connecting vertical wall of the can end, feeding a cut gasket liner ring from a stack of said rings and placing the same in axial alinement with a finished can end; forcing the liner ring over the interior drawn wall of the can end by a distortion of the inner circumferential edge thereof in order to seat the same within the circumferential groove or seat formed in the vertical wall of the can end, and finally discharging the gasket lined can end. In brief, the apparatus comprises means for first grooving the vertical connecting wall of the can end or cover to form an annular recess or retaining seat, positioning a cut ring liner in axial alinement with the grooved can end or cover, and applying the positioned liner to the flange of the can end by a distortion of the inner periphery thereof to pass the overhang or retaining shoulder of the circumferential groove or recess so that the distorted edge of the liner will spring or seat itself into the annular recess formed in the vertical connecting wall of the can end or cover when the same has passed the overhang or shouldered portion thereof.

The object of the present invention, therefore, is to provide mechanism to receive a can end or cover of the straight flanged type and while moving the same to an assembling

position or station, circumferentially grooving the vertical wall section thereof to provide a seat for retaining a ring positioned upon its straight flange, assembling a ring liner relative to said flange of the can end and holding the same united to the can end or cover without in any manner interfering with the proper functions of the liner or the flange of the can end or cover in their ultimate relation to the finished seam of a can when hermetically seamed thereto.

In order to comprehend the invention, reference should be had to the accompanying sheets of drawings, wherein,

Figure 1 is a general plan view of a proposed apparatus for carrying out the invention, disclosing intermittently rotating turrets for receiving unfinished can ends and gasket ring liners, conveying the same to an assembling station and placing the same in axial alinement, supplying the gasket liner to the flange of the can end or cover.

Fig. 2 is a front elevation of the machine disclosed by Fig. 1 of the drawings.

Fig. 3 is a plan sectional view taken on the line 3—3 of Fig. 2 of the drawings and viewed in the direction of the arrows, said view illustrating the driving mechanism actuating various parts of the apparatus.

Fig. 4 is a part sectional end elevation taken on the line 4—4, Fig. 1 of the drawings, and viewed in the direction of the arrows, said view disclosing the end feed mechanism and the groove forming mechanism with its associated parts.

Fig. 5 is a transverse sectional view of the can end holder with a stack of unfinished can ends therein, said view being taken on the sectional line 5—5 of Fig. 1 of the drawings, and viewed in the direction of the arrows, and illustrating the lowermost can end of the stack as being cut out and deposited within one of the seats of the turret for conveying the same to the grooving mechanism.

Fig. 6 is a view similar to Fig. 5, illustrating the can end or cover feed devices positioned for supporting the stack of ends or covers within the holder.

Fig. 7 is a transverse sectional view of the apparatus taken on the sectional line 7—7, Fig. 1 of the drawings, and viewed in the direction of the arrows, said view

illustrating the grooving means for the unfinished can ends or covers and the mechanism for actuating the same, also disclosing the drive means for imparting movement to the various working parts of the apparatus.

Fig. 8 is a detailed sectional part broken view illustrating the mechanism for grooving the can ends or covers, and in position for operating on a positioned can end or cover for the grooving thereof.

Fig. 9 is a fragmental sectional plan view taken on the sectional line 9—9, Fig. 8 of the drawings, and viewed in the direction of the arrows.

Fig. 10 is a sectional elevation taken on the line 10—10, Fig. 1 of the drawings and viewed in the direction of the arrows, said view illustrating a gasket liner in position for removal from its stack of liners and discloses a gasket liner in axial alinement with a positioned finished can end or cover and the means for assembling the liner relative to the flange of the positioned can end or cover.

Fig. 11, is an enlarged detailed sectional view disclosing one of the unfinished can ends or covers.

Fig. 12 is a similar view illustrating one of the finished can ends or covers and a gasket ring liner in axial alinement therewith, and the means for applying the liner to the flange of a can end.

In the drawings, reference being had more particularly to Figs. 1, 2 and 3 thereof, the numeral 1 is used to designate any suitable type of a supporting frame or table capable of sustaining the working parts of the apparatus, which in the present case, is illustrated as being upheld by the supporting legs 2. A horizontal drive shaft 3 is supported within the said frame structure and journaled for rotation in suitable bearings 4, mounted upon an intermediate horizontal plate 5 secured to the supporting legs 2, and the said shaft 3 carries at its outer extremity a belt pulley 6 having power applied thereto from any outside source not illustrated in the drawings.

A horizontally disposed can end carrying a turret 7 is mounted above the table 1, Fig. 7 of the drawings, the same being secured to a vertical shaft 8, which is journaled in bearings 9 and 10, formed respectively in the table 1 and plate 5, the said shaft 8 and turret 7, being intermittently rotated through the medium of suitable Geneva mechanism, comprising a Geneva wheel 11, Fig. 3 of the drawings, fixed upon the shaft 8 above the plate 5, and which is actuated by means of a crank arm 12, carrying a following roller 12' which is adapted to move into and out of the radial slots formed in the Geneva wheel 11, the said arm 12 being secured to a vertical shaft 13, which receives continuous rotation from the driving shaft

3, through the medium of the bevel gears 14 and 15, mounted respectively on the shafts 13 and 3, Figs. 3 and 4 of the drawings. The turret 7 is provided or formed with a series of spaced circular apertures 16, Figs. 70

1 and 7 of the drawings, each of the said openings or apertures being of a diameter to receive an unfinished can end or cover so as to be supported by the table 1, the said openings being so disposed as during the 75 rotary movement of the turret 7 to pass beneath a magazine or holder 17, for the unfinished or ungrooved can ends or covers 18.

This can end or cover holding magazine is mounted above the horizontal table 80 1, Fig. 2 of the drawings, and is situated adjacent to and overhangs the turret 7. The said holder is provided with a circular opening or seat 19, Fig. 1 of the drawings, which stands in axial alinement with one of the openings 16 of the turret 7, when the said turret is at a state of rest. The stack of horizontally disposed unfinished or ungrooved can ends or covers 18 rest within the opening 19 and within upwardly extended bars 20, which constitute a continuation of the holder or magazine for the stack of ends or covers. The ends or covers are supported within the stack by means of oscillating feed bars 21, Figs. 1, 4, 5 and 6 of the 95 drawings. Each feed bar 21 is provided with a longitudinally disposed notch or groove 22, which extends substantially the length of the feed bars within the opening 19, of the magazine or holder for the ends 100 or covers, and said notches when positioned as illustrated in Fig. 6 of the drawings, receive the flange of the lowermost can end 18' of the stack of can ends or covers 18, and thereby support the entire stack. A partial 105 rotation or oscillatory movement imparted to the bars 21 turn the notched portions thereof downwardly from the position shown in Fig. 6 of the drawings to that illustrated by Fig. 5 of the drawings, which 110 throw or movement of the said bars results in a lowering of the lowermost can end 18' and the dropping thereof from the supporting notches 22 within one of the apertures 115 16 of the turret 7 which at such time stands in axial alinement therewith, Fig. 5 of the drawings, the remaining portion of the stack at such times being supported by the flange of the bottom-most can end or cover resting on the upper surfaces of the said bars.

The turning or oscillatory movement of the bars 21 is obtained from the rotation of the drive shaft 3 through the medium of the mechanism illustrated in Fig. 4 of the drawings, and which comprises the gears 125 23 mounted on the outer ends of the bars 21, Figs. 1 and 4 of the drawings, meshing with the rack portions 24 of a U-shaped yoke bar 25, which bar works in guide-ways 26 formed in a supporting bracket 27 de- 130

pending from the table 1. The lower end of the bar 25 is pivotally connected to the inner end of a lever 28, which lever is fulcrumed at 29, to the supporting frame structure of the apparatus, and at its outer end is pivoted to the upper end of a rod 30, which is connected at its lower end to an eccentric strap 31 of an eccentric 32, which said eccentric is fixed to the drive shaft 3. By 10 means of this connection, with each rotation of the drive shaft 3, the feed bars 21 are oscillated so as to cause a picking off or cutting out of the lowermost can end 18' of the stack of ends within the holder, and a 15 deposit thereof within one of the pockets 16 of the turret 7. The operating mechanism thus described is so timed as to deposit an unfinished end or cover within one of the pockets of the turret 7, when said turret 20 is at a state of rest with the pocket or opening in axial alinement with the magazine or holder of the stack of can ends.

After an ungrooved or unfinished can end has been fed from the stack within the magazine or holder to within one of the apertures or openings of the turret 7, the said turret has imparted thereto a step rotation, the movement of which causes the seated unfinished can end or cover 18', to slide over 30 the upper surface of the table 1 until the turret is brought at rest at the groove forming station of the apparatus, and which station is indicated by the letter B, Fig. 1 of the drawings, the grooving mechanism for 35 the said can end or cover being illustrated in detail by Figs. 7, 8 and 9 of the drawings.

At the grooving station of the apparatus for forming a circumferential groove in the vertical wall *a* which connects the outstanding flange *a'* of the unfinished can end or cover to the body portion *b* thereof, Fig. 11 of the drawings, there is situated a grooving roller which coöperates with a circular grooving track, the roller acting against the inner 40 surface of the wall *a* of the can end or cover and bending the same over the forming edge of the circular track, which roller and cover at such times move together during a rest period of the turret 7 and operate in timed 45 relationship, one with the other. This mechanism will be readily understood by reference to Figs. 3 and 7 of the drawings, it being noted that a vertical shaft 33 extending above the table 1 and through the 50 plate 5 is journaled for rotation in bearings 34 and 35 of the said table 1 and plate 5, respectively, and is also journaled in a bearing 36 of a bracket 37, mounted upon the upper surface of the table 1, adjacent to 55 and partially overhanging the turret 7 at the groove forming station D, Fig. 1 of the drawings. The said shaft 33 receives its motion of rotation from the shaft 13 through the medium of the spur gears 38 and 39, 60 mounted respectively upon the shafts 33 and 13, Fig. 3 of the drawings. Beneath the turret 7 and in radial alinement with the turret shafts 8 and the shaft 33, Fig. 7 of the drawings, there is formed in the table 1, a circular pocket 40 in which is mounted 70 for rotation a die block 41; the said block is provided with gear teeth 42 which mesh with a gear 43 fixed to the shaft 33, so that the rotary motion of the said shaft 33 is transmitted to the block 41 in order to cause 75 the said block to slowly revolve about its own axis. The upper face of the block 41 stands flush with the top of the table 1, so that as the turret 7 revolves across the surface of the table 1 the unfinished can end 80 or cover held in one of the pockets 16 is slid over the top of the said block and over a circular seat 44 formed in the upper face of said block, so as to stand in axial alinement with said seat when the turret 7 is 85 brought to a state of rest, but being held out of the seat 44 by means of a spring-held ejector plate 45 which is slidably mounted within the block 41 and which normally rests with its upper face flush with the upper surface of the table 1, Fig. 8 of the drawings.

A grooving roller 46, is secured to the lower end of a vertically disposed spindle 47, Figs. 4, 7 and 8 of the drawings, which spindle is journaled in an eccentric bushing 48 mounted for rotation and longitudinal movement above the table 1, the same working within a bearing 49 of the bracket 37, Fig. 7 of the drawing. This forming roller 100 46 is adapted to move downwardly to forming position within the circular connecting wall *a* of a can end or cover and to be moved radially to coact with a forming track of the die-block, and also to rotate for propelling 105 the wall *a* of the can end around its circular length during the groove forming action. When the unfinished can end or cover 18' resting within one of the pockets 16 of the turret 7 has been moved to its position of 110 rest upon the ejector plate 45, and above the circular seat 44 of the die-block 41, the grooving roller 46 is moved downwardly to bear against the can end 18' for forcing the same and the supporting ejector 45 to the position 115 shown in Fig. 7 of the drawing. The parts are then positioned for the grooving of the wall member *a* of the can end or cover, at which time the circular outstanding straight flange of the can end or cover is still within 120 the sphere of the turret pocket. The lowering of the forming roller 46 and its spindle 47 is accomplished in the following manner: Referring to Figs. 1, 2, 3 and 7 of the drawings, it will be noted that a vertical shaft 50 is journaled for rotation in a bearing 51 of the table 1, and in a bearing 52, of the bracket 37, the said shaft receiving rotation from the shaft 33 by means of a gear 53 fixed to the lower end of the shaft 50 125 130

meshing with the gear 38 fixed upon the shaft 33. To the upper end of the shaft 50 is secured a cam 54 which is provided with a cam-groove 55 which operates upon a cam 5 following roller 56, which said roller is carried by one end of a lever 57 fulcrumed upon a rock shaft 58, which shaft oscillates within a bearing 59 formed on a bracket 60, mounted upon the table 1 adjacent to and partially 5 over-lapping the turret 7, Fig. 1 of the drawings. The opposite end of the lever 57 carries a roller 61, which works within an annular groove 62, of a collar 63, secured to the upper end of the eccentric bushing 48, 10 Fig. 7 of the drawings. This construction permits of an oscillation of the collar 63 and permitting a raising and lowering of the eccentric bushing 48 therewith. The forming roller 46 and its associated spindle 20 47, receives rotation from the shaft 33, through the medium of the mating gears 64 and 65, the former being secured to the upper end of the spindle 47, and the latter fixed to the upper end of the shaft 33. A die-forming track 66, Figs. 7 and 8 of the drawings, is provided or made in the side wall of the seat 44, and the same constitutes the circular die-grooving track, and into this track or die the vertical wall member *a* of the can end 25 or cover is forced or pressed by the action of the forming roller 46, which is moved toward the said track to compress the wall member *a* of the can end or cover therein, by means of the action of the eccentric bushing 48 mounted on the rotating spindle 47. The forming roller is moved toward and from the die-forming track through the medium of a cam 67, secured to the shaft 50 above the bracket 37 and beneath the cam 54 30 operating against a cam following roller 68, carried upon one arm of a lever 69, loosely mounted upon the shaft 33, and the opposite end of the said lever 69 terminates in a gear tooth segment 70, which extends into and 35 meshes with gear teeth 71 cut in the outer surface of the eccentric bushing 48 beneath the collar 63. A compression spring 72 fastened to the lever 69 and the bracket 37 holds the roller 68 firmly in contact with the cam 50 40 45 50 55 60 65 70 75 80 85 90 95 100 105 110 115 120 125 130 described with a rotary movement, to groove circumferentially the wall member *a* of the can end or cover, and which grooving provides an overhang at the point of union of the wall member *a* with the body member *b* 60 of the can end or cover. By reference to Fig. 9 of the drawings, it will be noted that the peripheral length of the die-forming groove 66 is in excess of the peripheral length of the grooving wall of the can end, 65 which permits of the same being fully grooved before the die-block 41 has completed one revolution. A portion of the forming groove 66 is cut away, as at 73 (Fig. 9), and such cut away portion passes over a portion of the completely formed groove of 70 the can end immediately after the grooving operation. After the formation of the groove in the wall member *a* of the can end or cover, the grooving roll 46 is partially lifted by the hereinbefore described cam operated 75 mechanism, and the ejector plate 45 under the influence of its spring action raises and lifts the grooved can end through the opening or cut-away portion 73 to its normal position above the table 1, it being understood that the said end or cover at all times has its peripheral flange within the turret pocket 16, it merely rotating within such pocket during the grooving operation. The eccentric bushing 48 is then oscillated to 80 retract the roller 46 horizontally from out of the groove in the can end or cover, when further lifting of said roller 46 restores the mechanism to normal position awaiting a further cycle of operation, it being noted by 90 reference to Figs. 4 and 7 of the drawings that the face length of the teeth of the gear 64 is extended to allow vertical movement upon the gear 65 without disengagement. As illustrated in Figs. 1, 2 and 10 of the 95 drawings, a gasket carrying turret 74 is mounted within a depressed circular seat 75, formed in the table 1 adjacent the turret 7, the upper surface of the said turret 74 being flush with the upper surface of the table 1 of the frame structure. The turret 74 is secured to a vertical shaft 76, which receives intermittent rotation from the Geneva operated turret shaft 8 by means of the spur gears 77 and 78, fixed respectively 100 to the lower end of the shafts 8 and 76, Figs. 2 and 3 of the drawings. The turret 74 is formed with pockets 79, in which are slidably held core pieces 80, the outside diameter of which is the same practically as 105 the inside diameter of a cut gasket ring 81. A circular seat 82 is formed in the upper surface of the turret 74 adjacent to and concentric with each of the pockets 79, said seats being of a diameter sufficient to receive a gasket liner therein and of a depth co-extensive with the thickness of said liners. A gasket holder or magazine 83 having extension rods 84 is secured to a bracket 83' projecting from the supporting 110 frame of the apparatus, and the said holder is positioned at a liner applying station C, Fig. 1 of the drawings, and partially overhangs the turret 74. A circular seat opening 85 of the holder or magazine 83 is adapted to hold a stack of horizontally disposed gasket ring liners 81, in axial alignment with the circular seat 82 of the turret 74, when the same is in a position of rest, at which time the core piece 80, below the said holder 115 120 125 130

83 is held in an upward position (Fig. 10) by means of the springs 80', so that the top surface thereof lies flush with the top surface of the turret 74. When the said turret 5 74 stands at rest with one of its circular seats 82 in axial alinement with the opening of the gasket liner holder or magazine, the lowermost gasket liner 81' of the stack, under pressure of the weight 86 placed be- 10 tween the rods 84 of the holder, moves within the said seat 82 of the turret and completely fills the annular channel formed by the vertical wall of said seat and the outer wall surface of the spring held block 15 80, Fig. 10 of the drawings, it being understood that the positioning of a gasket liner within the annular chamber thus formed is done simultaneously with the forming of a groove within a can end as previously de- 20 scribed.

On the next step rotation or movement of the turret 7 and the turret 74, the grooved end or cover 18' within one of the pockets 16 of the turret 7, is swept from the position of rest at station B over the upper surface of the table 1 to the position or station D Fig. 1 of the drawings, at which time the turret 74 with a gasket liner 81' held thereby has moved to place the gasket liner in 25 axial alinement with the can end or cover carried by the turret 7, or in other words, the turret 74 and the turret 7, carrying respectively a gasket liner and a grooved can end or cover are brought to a state of rest 30 at the station D with the members held thereby in axial alinement. When the formed end or cover and the gasket ring liner have reached the said position D, which is the assembling station of the apparatus, and stand in axial alinement, an assembling plunger 87, Figs. 1 and 10 of the drawings, comes into action for assembling the can end or cover and the positioned gasket liner. The said assembling plunger 87 35 is provided with an upwardly projecting stem 88, Figs. 7 and 10 of the drawings, which stem is slidably mounted within a suitable bearing 89, of the bracket 60, the plunger 87 standing in axial alinement with the positioned can end or cover at the assembling station. A lever 90, pivotally connected to the upper end of the stem 88 of the plunger 87 is connected at its opposite end to the rock-shaft 58, Fig. 1 of the drawings, which shaft 58 is cam-operated as heretofore described. With the turrets 7 and 45 74 standing at rest at the assembling station, the plunger 87 descends within the opening 16, of the turret 7 and acting against the positioned can end or cover forces the same downwardly against the spring action of the core piece 80. In order to permit of the body member 6 of the positioned can end or cover moving downwardly 60 within the positioned pocket 79 of the tur-

ret 74, the same is cut away below the plane of the seat 82 so as to provide a clearance space 91. It will be understood that the inner diameter of the gasket ring liner is slightly less than the enlarged outer diameter of that portion of the can end or cover adjacent the groove, or the overhang portion of the said groove, so that during the passage of the body member 6 at the overhang edge of the circumferential groove of the member a of the can end or cover through the gasket liner, the latter is bent backwardly distorted or expanded on its inner diameter, and when the said enlarged portion of the end or cover has passed 70 through the inner diameter of the gasket ring said distorted diameter of the gasket liner is restored or springs back to normal position and fits snugly within the circumferential groove formed in the wall member 75 a of the end or cover 18'. On the plunger 87 being lifted or moved away from the lined can end or cover, the spring 80' raises the core-piece 80 and the lined can end 18'' resting thereon, and moves or positions the 80 lined can end wholly within the opening 90 of the turret 7.

After the operation just described, the turret 7 has imparted thereto a part rotation or step movement, which sweeps or moves the gasket lined end 18'' from its position at the assembling station D to the position or discharge station E, Fig. 1 of the drawings, at which station, the gasket lined can end or cover falls by gravity through an 95 opening 92, cut in the table 1 into a discharge chute 93, Fig. 7 of the drawings, by means of which the gasket lined end is conveyed to any suitable place of deposit.

From the foregoing it will be noted, that 100 the cam end or cover to be grooved is fed into one of the pockets of the turret 7, at the station A, and is then transferred by the turret 7 to the grooving station B, at which station the vertical wall member a of the 105 can end or cover is grooved to receive the inner circumferential edge of a gasket liner, the turret 7 then advancing or moving with the grooved can end or cover to the assembling station D. While these operations are 110 taking place a gasket ring liner is delivered into one of the pockets of the turret 74 at the feed station C for the ring liners, and the said liner is transferred from the said station and brought or positioned into axial 115 alinement with the can end or cover at the assembling station D, where the parts are assembled, after which the rotary motion of the turret 7, conveys the assembled gasket lined can end or cover to the discharge station 120 E, from whence the same is discharged 125 from the apparatus.

The apparatus has been illustrated and described in its preferred embodiment for the carrying out of the invention, but I do 130

not wish to be understood as limiting or restricting the invention to the detailed construction of the working parts shown and described, but on the contrary wish to be understood as claiming as broadly as the state of the art will permit the interconnected working instrumentalities whereby the can end or cover is circumferentially grooved or recessed to receive a gasket liner, a gasket liner brought into axial alinement with the grooved can end or cover and the parts assembled by causing a distortion of the inner circumferential edge of the gasket liner as the same is passed over the overhang formed by the circumferential grooving of the wall member *a* of the can end or cover.

It is apparent, that if so desired, the can holder or magazine may be filled with a stack of previously grooved can ends or covers, in which event, the groove forming mechanism may be eliminated, and the grooved can ends or covers conveyed or transferred from the can end feed station direct to the assembling station. However, preference is given to embodying the grooving mechanism in the apparatus for assembling the ends and gasket liners.

Having thus described my invention what I claim as new and desire to protect by Letters Patent is:

1. In an apparatus for the described purpose, the same comprising means for receiving and positioning straight flanged can ends at a forming station and transferring the same to an assembling station, mechanism situated at the forming station for circumferentially grooving the wall connection between the straight flange and the body member of a can end positioned at said station, means for positioning a gasket ring liner at the assembling station and in axial alinement with a grooved can end there positioned, mechanism at said station for assembling the can end and gasket liner by distorting the inner peripheral edge portion of the liner to pass the overhang of the groove formed in the can end in order to seat within the groove, and devices for ejecting the gasket lined end.

2. An apparatus for the described purpose provided with a forming station and an assembling station spaced therefrom, the same comprising a horizontally disposed carrier having a plurality of spaced apertured can end receiving openings formed therein, devices for delivering successively straight flanged non-grooved can ends into the receiving openings of the said carrier, means for actuating the carrier to position a can end held therein successively to the forming station and the assembling station of the apparatus, mechanism situated at the forming station for grooving circumferentially the wall connection between the outstanding flange and body member of the can end posi-

tioned at said station, an aperture carrier for receiving a gasket ring liner and positioning the same in axial alinement with a can end at the assembling station, mechanism situated at said station for assembling the alined members by distorting the inner periphery of the liner to pass the overhang of the can end to fit within the groove formed therein, and means for operating the mentioned interconnected working instrumentalities in timed relation.

3. In an apparatus for the described purpose, the combination with mechanism for grooving circumferentially the connection wall member of a flanged can end, a horizontally disposed apertured rotatable turret for receiving ungrooved can ends and advancing the same successively to the grooving mechanism and to an assembling station spaced therefrom, a horizontally disposed apertured turret for receiving gasket ring liners and advancing the same to the assembling station and in axial alinement with a positioned grooved can end, mechanism at said station for assembling the alined members by distorting the inner peripheral edge of the liner to pass the overhang of the formed groove of the can end to seat therein, and for actuating the described parts in timed relation.

4. In an apparatus for the described purpose, the combination of means for forming an exterior circumferential groove in the vertical shoulder of a can end to receive and retain a ring liner therein, mechanism for receiving and alining such grooved can end and a gasket liner whose inner diameter is less than the diameter of the ungrooved portion of said vertical shoulder, vertically movable means for assembling the said axially alined members by causing a distortion of the inner peripheral edge of the ring liner as it is carried over the said ungrooved portion of the vertical shoulder and into said circumferential groove, and devices for actuating the described working parts in timed relation.

5. In an apparatus for assembling gasket liners relative to can ends for the hermetic closure for sanitary cans, the same comprising means for receiving flanged can ends and circumferentially grooving the connecting wall member between the flange and the body of the can end to form a peripheral shoulder to enter within the mouth of a can, means for placing the grooved can end and a gasket ring liner in axial alinement, and associated devices for applying the ring liner to the flange of a can end by causing the shouldered portion of the can end to distort the inner circumferential edge of the liner to pass said shoulder and seat itself within the groove formed in the connecting wall member of the can end.

6. An apparatus for applying gasket liners to straight flanged can ends, which

consists of associated interconnected working instrumentalities for receiving a can end and forming in the outer surface of the vertical connecting wall member thereof, a 5 peripheral groove, placing a gasket ring liner in axial alinement with the said grooved can end, applying the gasket liner to the flange of the can end by a distortion of its inner circumferential edge to clear the 10 overhang of its grooved wall member, and mechanism for actuating the mentioned interconnected working instrumentalities in timed relation.

7. In an apparatus for the described purpose, the combination with a block having 15 a seat formed therein for the reception of a portion of an ungrooved can end, and provided with a die-ring, means for positioning an unflanged can end onto the seat of the 20 said block, a rotary vertically and radially movable forming roll adapted to move within said seat and coact with the die thereof for circumferentially grooving the outer surface of the connecting wall member of 25 the can end, means for imparting rotary, vertical, and radial movement to said die-forming roller, devices for ejecting a grooved can end from within the seat of the said block, means for transferring the grooved 30 end to an assembling station, mechanism for positioning a gasket ring liner at said station beneath and in axial alinement with the positioned can end, devices at said station for assembling the axially alined members 35 by distorting the inner circumferential edge of the said liner to pass the overhang of the grooved connecting wall member of the can end to seat within the groove thereof, and devices for ejecting the gasket lined 40 can end.

8. An apparatus for the described purpose, having embodied therein a can end feed station, a groove-forming station, a gasket liner feed station and an assembling 45 station, an apertured turret for receiving ungrooved can ends and transferring the same respectively to the forming station and the assembling station of the apparatus, a can end holder or magazine situated at the can 50 end feed station, a ring liner magazine or holder situated at the feed station for the gasket liner, means for delivering the lowermost can end of a stack of held ends from the holder thereof into one of the apertures 55 of the transfer turret when the same is at a state of rest, mechanism at the forming station for peripherally grooving the vertical connecting wall member of a can end, said means comprising a fixed circular die and 60 a rotary, vertically and radially movable forming roll, a horizontally disposed apertured turret movable beneath the holder or magazine for the ring liners adapted to receive in one of its apertures the lowermost 65 ring liner of a stack held within the said

holder and to transfer the same to the assembling station and in axial alinement with a grooved can end held thereabove, vertically movable means at said station for assembling the alined members by causing a distortion of the inner peripheral edge of the gasket ring liner to pass the overhang of the connecting wall member of the can end so as to seat within the groove thereof, and means for actuating the mentioned working 75 parts in timed relation.

9. In an apparatus for the described purpose the combination with a groove forming die, of a traveling carrier movable to successive station including a grooving 80 station and having means for positioning a straight flanged can end relative to said die with its vertical connecting wall member in parallel relation to said die, a die forming roller at the grooving station adapted to 85 coact with said die for grooving peripherally the outer surface of the connecting wall member of a positioned can end, and means for imparting rotary vertical and radial movement to said forming roll. 90

10. In an apparatus for the described purpose, the same comprising means for receiving a straight flanged can end, devices coacting therewith for grooving peripherally the outer surface of the vertical connecting wall member of the can end, means for positioning in vertical alinement with the grooved can end a gasket ring liner, the internal diameter of which is slightly less than the diameter of the overhang of the 100 groove formed in the can end, and means for assembling the alined member by distorting the inner peripheral edge of the liner to pass the overhang of the can end to seat within the groove thereof. 105

11. In an apparatus for the described purpose, the combination of interconnected mechanism for forming an exterior circumferential groove in the described vertical connecting wall of a can end, means for 110 placing said grooved can end and a gasket ring liner in axial alinement, and means for assembling said alined members by axial pressure.

12. In an apparatus for the described purpose, the combination with mechanism for grooving the outer surface of the connecting wall member of a straight flanged can end, devices for delivering the grooved end to an assembling station, means for positioning a gasket ring liner at said station in axial alinement with the grooved can end, and mechanism for assembling said alined members by causing a distortion of the inner circumferential edge of the liner to 125 clear the overhang of the can end groove to seat therein.

13. In an apparatus for the described purpose, the combination with mechanism for positioning at an assembling station a 130

flanged can end having a circumferential groove formed in the outer surface of its connecting wall member, a turret provided with a plurality of apertures each having 5 a circumferential seat for receiving ring liners, mechanism for actuating said turret for transferring gasket liners to the assembling station and in axial alinement with a can end positioned at said station, a spring 10 held core piece in each aperture of the turret coacting with the vertical wall of the liner seat thereof to provide an annular chamber for the reception of the liner as moved onto its seat, and vertically movable 15 means at the assembling station for forcing the can end toward the liner and applying the same to the flange thereof by causing a distortion of the inner circumferential edge of the liner to pass the overhang of 20 the groove formed in the connecting wall of the end.

14. The combination of means for forming an exterior circumferential groove in the described vertical wall of a can end, 25 means for receiving and holding in axial alinement said grooved can end and a gasket ring liner whose inner diameter is less than that of the ungrooved portion of said vertical wall, and means for moving the 30 can end axially toward the liner for assembling the latter in said circumferential groove.

15. In an apparatus for the described purpose, the combination of interconnected 35 mechanism for forming an exterior circumferential groove in the described vertical connecting wall of a can end, means for placing said grooved can end and a gasket ring liner in axial alinement with the can end 40 arranged with the bottom side toward and above said gasket ring liner, and means for

assembling said alined members by axial pressure.

16. In an apparatus for the described purpose, the combination with a die for forming a circumferential groove in the outer surface of the connecting wall of a flanged can end, of a forming roll for coacting with the die for forming said groove, interconnecting working instrumentalities for imparting rotary, vertical and radial movement to the forming roll and an endless carrier for positioning a succession of flanged can ends to be grooved within the sphere of said die and forming roll. 55

17. In an apparatus for the described purpose having a can end groove forming station and an assembling station spaced therefrom, means for receiving a flanged can end and advancing the same to the groove forming station and from said station to the assembling station, mechanism situated at the forming station for grooving the outer surface of the connecting wall member of the end, means for delivering at the assembling 60 station and in axial alinement with a positioned grooved can end a ring liner whose inner diameter is less than that of the body member of the can end, and mechanism at the assembling station for applying the ring 65 liner to the flange of the can end by causing a distortion of its inner circumferential edge to clear the overhang of the groove in the can end and seat within said groove. 70

In testimony whereof I have signed my 75 name to this specification in the presence of two subscribing witnesses.

IVAN D. THORNBURGH.
